(57) **CLAIM**

The ornamental design for a wind detection device as shown and described.

DESCRIPTION

FIG. 1 is a perspective view of the wind detection device. FIG. 2 is a front elevation view of the wind detection device. FIG. 3 is a rear elevation view of the wind detection device. FIG. 4 is a top plan view of the wind detection device. FIG. 5 is a bottom plan view of the wind detection device. FIG. 6 is a left side elevation view of the wind detection device; and, FIG. 7 is a right side elevation view of the wind detection device.
